DESIGN FOR A PICTURE FRAME OR SIMILAR ARTICLE

Herman Bush, New York, N. Y.

Application February 24, 1944, Serial No. 112,688

Term of patent 3½ years

(Cl. D29—20)

To all whom it may concern:

Be it known that I, Herman Bush, a citizen of the United States, residing at 460 Audubon Avenue, city of New York, in the county of New York and State of New York, have invented a new, original, and ornamental Design for Picture Frames or Similar Article, of which the following is a specification, reference being had to the accompanying drawing, forming part thereof.

Figure 1 is a perspective view of the picture frame or similar article, showing my new design; and Figure 2 is a vertical cross section along the line 2—2 of Figure 1.

I claim:

The ornamental design for a picture frame or similar article, as shown.

HERMAN BUSH.
